FIG.1

FIG.2

FIG.3

FIG. 4

FIG. 5

FIG. 6

Fig. 1 is a perspective view of the combination brief case and writing support looking into the interior of the same and seen in half open position;

Fig. 2 is a perspective view similar to Fig. 1, but looking toward the outer surface and drawn to a reduced scale;

Fig. 3 shows the combination brief case and writing support in closed position and drawn to a further reduced scale;

Fig. 4 is a top plan view thereof shown open and looking into the inner surface;

Fig. 5 is a top plan view thereof looking onto the outer surface;

Fig. 6 is an end elevation view thereof according to Fig. 4.

The design for the combination brief case and writing support disclosed is characterized by a rectangular configuration of three hinged panels in tandem relation, in fully open condition thereof, with two of said panels having oppositely directly pockets opening endwise, the

remaining panel being coextensive with the outer faces of said pockets forming a flap with the end edges thereof converging outwardly and overlying the two panels in superposed position in closed condition of said brief case, all as shown.

I claim:

The ornamental design for a combination brief case and writing support, substantially as shown and described.
